(57) **CLAIM**

The ornamental design for a decompression needle device case, as shown and described.

DESCRIPTION

FIG. 1 is a perspective view of a decompression needle device case showing our new design;

FIG. 2 is another perspective view thereof;

FIG. 3 is a left side plan view thereof;

FIG. 4 is a right side plan view thereof;

FIG. 5 is a top plan view thereof;

FIG. 6 is a bottom plan view thereof;

FIG. 7 is a front plan view thereof; and,

FIG. 8 is a rear plan view thereof.
